UNITED STATES PATENT OFFICE.

CHARLES E. TRAXEL, OF ROME, NEW YORK, ASSIGNOR TO ROME WIRE COMPANY, OF ROME, NEW YORK, A CORPORATION OF NEW YORK.

BRAIDING-MACHINE.

1,058,206.

Specification of Letters Patent.

Patented Apr. 8, 1913.

Application filed February 23, 1912. Serial No. 679,222.

To all whom it may concern:

Be it known that I, CHARLES E. TRAXEL, a citizen of the United States, residing at Rome, in the county of Oneida and State of New York, have invented an Improvement 5 in Braiding-Machines, of which the following is a specification.

In the common form of braiding-machines for covering wire with silk, cotton and other threads, the threads are repeatedly drawn from supplies arranged on the supply-holders, and when it is attempted to drive the machines at a high speed the threads are withdrawn so quickly that they are frequently broken and the gain incident to running the machine at a high speed is more than offset by the loss due to breakage. Usually these machines are provided with automatic means to stop the machine in case 10 a thread breaks, said means consisting of a weight adapted to be lifted by the thread when the latter is pulled taut, and arranged to act by gravity when the thread breaks, thereby to control the operation of a stop-motion or clutch for the machine. This 15 form of automatic stopping means is also objectionable when attempting to drive the machine at a high speed.

This invention has for its object to provide 20 each supply-holder with a tension-device in the form of a friction-brake, which engages the base of the supply-holder and exerts thereon a moderate pressure, whereby its rotary motion is resisted, but is not restrained or checked; and also to provide a take-up arm for the thread, movement of which is opposed by a spring, said arm being arranged to be engaged by the thread and to be operated by a pull upon the thread, 25 and said arm operating when raised to a predetermined elevation to move the friction brake, so as to relieve the tension on the supply-holder, thus admitting of sudden withdrawals of the thread from the supply-holder, which movements are yieldingly resisted, and as a result the thread will not be broken even though the machine is driven 30 at a high speed.

The invention also has for its object to

construct and arrange a controlling-member 50 for the stop-motion or clutch of the machine, in the path of movement of said take-up arm, whereby in case a thread breaks and said take-up arm thereupon resumes its normal position, said controlling-member will 55 be operated to control the stopping of the machine.

Figure 1 is a side elevation of a traveling-carrier and supply-holder, of a braiding-machine embodying this invention. Fig. 60 2 is a front elevation of the same. Fig. 3 is a rear elevation of the same. Fig. 4 is a horizontal section taken on the dotted line 4-4, Fig. 1. Fig. 5 is a modification to be referred to. 65

10 represents the traveling-carrier; 12 a post thereon, and 13 a supply-holder rotatably mounted on said post, said supply-holder having a circular base 14. A collar 15 is rigidly secured to the post at or near 70 the top of the supply-holder, which prevents axial movement of the supply-holder in an upward direction. As here shown, for the purpose of illustrating one embodiment of my invention, the friction-brake is arranged 75 beneath the circular base of the supply-holder, and is constructed and arranged to exert a moderate pressure thereon in an upward direction, thereby to resist its rotary motion, but not to restrain or lock it. As 80 represented in Figs. 1 to 4, said friction-brake consists of a pair of bosses 20, 20, a frame 21 bearing said bosses which is pivotally supported on a short shaft or pin 22, arranged at right angles to the post 12, and 85 passing through a hole in an extension 23 on said post. Said frame is movable on the shaft 22 to cause the bosses to engage and disengage the under side of the circular base 14. Said frame 21 has a lug 25, which extends downward a short distance, adapting 90 it to be engaged by means provided for moving the frame in a direction to cause the bosses to disengage the circular base. Said frame is acted upon by a spring 30, arranged on the extension 23 on the post, to move the frame in an upward direction to 95 cause the bosses to continuously engage the

circular base with a yielding pressure. This form of friction-brake is simple and operates effectively, but my invention is not limited to the particular form here shown, nor 5 to a friction-brake arranged to exert its pressure in any particular direction. Also as here shown 40 represents a take-up arm for the thread 41, and has a hook 42 or other means at its extremity, for engagement with 10 the thread, which thread passes over hooks or other means arranged on an upright post 35 on the traveling-carrier. Said take-up arm is secured to a pivot-shaft 43, which extends through a hole in the extension 23 on 15 the post, and which has arranged on it a spring 44, attached at one end to it and at the other end to said extension, said spring acting to move the take-up arm in a downward direction and thus to oppose the lifting movement of said arm, due to a pull 20 upon the thread. For the purpose of attaching one end of the spring to the shaft in an adjustable manner, a disk 45 having notches in its periphery is secured to the 25 shaft, and the end of the spring 44, is arranged in any of the notches in said disk, and may be removed from any notch and placed in another easily and quickly. The take-up arm has a hub 50 embracing the 30 pivot-shaft, which is formed with a shoulder 51, so arranged as to engage the lug 25 on the friction-brake when the arm is lifted to an extreme position, as represented by dotted lines Fig. 1, and by thus engaging 35 said lug to move the friction-brake, so as to relieve partially or wholly the pressure on the circular base of the supply-holder. A sudden pull on the thread acts to lift the 40 take-up arm into its extreme elevated position or thereabout, and to operate the friction-brake to relieve the pressure on the supply-holder.

The take-up arm is moved downward by its controlling-spring and occupies a position with its extremity near the base of the traveling-carrier when there is no tension or pull upon the thread, and herein advantage is taken of this condition by utilizing the take-up arm to control a stop-motion or 50 clutch for the machine. As shown, 60 represents a controlling-member for the stop-motion or clutch, which may be made as a lever, pivotally supported on the traveling-carrier at a point intermediate its length, or 55 otherwise and elsewhere supported, and one end of said controlling-lever is arranged in the path of downward movement of the take-up arm, so as to be engaged by said arm for the purpose of moving the lever. 60 Said lever, however, will only be engaged and operated when the take-up arm occupies its lowermost position, so that when the thread breaks and said arm assumes this

position it will move the controlling-member 60 to control the stopping of the machine. 65

In Fig. 5 the take-up arm 70 is constructed to operate similarly to the take-up arm above described, but its hub 71 is made as a cam which is supported directly beneath the 70 circular base of the supply-holder, and engages said base in all positions of the take-up arm, except when said arm is lifted by a pull upon the thread into its most elevated position or thereabout, and at such time the 75 cam 71 is moved far enough to partially or wholly disengage the circular base of the supply-holder and thereby relieve the tension thereon.

My invention herein described is to be 80 especially contrasted with a device having means to lock the supply-holder, as I have found in practice that any means which positively locks the supply-holder cannot be operated quickly enough to prevent the 85 thread from breaking when pulled suddenly or jerked by repeated withdrawals of the thread, while the machine is operating at a high speed.

I claim:—

1. In a braiding-machine, the combination of a rotatable supply-holder having a base, a traveling-carrier therefor, means to hold said supply-holder against axial movement, a friction-brake-member arranged beneath 95 the base of the supply-holder and pivotally supported on the carrier and arranged to engage the under side of the base of the supply-holder, a take-up arm adapted for engagement with the thread having means 100 to operate the friction-brake to relieve the pressure on the supply-holder, and a spring to oppose movement of said take-up arm, substantially as described.

2. In a braiding-machine, the combination of a rotatable supply-holder having a base, means to hold said supply-holder against axial movement, a traveling-carrier, a friction-brake borne by the carrier which engages the under side of the base of said supply-holder and exerts a pressure thereon in the direction of the axis thereof, a take-up arm, adapted for engagement with the thread, arranged to actuate said friction-brake to relieve the pressure on the supply-holder, and a spring to oppose movement of said take-up arm, substantially as described. 110

3. In a braiding-machine, the combination of a rotatable supply-holder having a base, a traveling-carrier for said holder having means to prevent axial movement of said holder, a pivoted frame arranged beneath the base of the holder having portions to frictionally engage said base, a spring to hold said portions in engagement with the base, a lug on said frame, a take-up arm 120

adapted for engagement with the thread, said arm having a hub with a shoulder arranged for engagement with said lug to move said frame and relieve the pressure of 5 its engaging portions on the base, substantially as described.

In testimony whereof, I have signed my

name to this specification, in the presence of two subscribing witnesses.

CHARLES E. TRAXEL.
